Inventor,
Edward E. Josef
By W. T. Miller
Attorney.

UNITED STATES PATENT OFFICE.

EDWARD E. JOSEF, OF BUFFALO, NEW YORK.

CLAMP FOR MOLDERS' FLASKS, &c.

SPECIFICATION forming part of Letters Patent No. 424,988, dated April 8, 1890.

Application filed February 24, 1888. Serial No. 265,125. (No model.)

To all whom it may concern:

Be it known that I, EDWARD E. JOSEF, a citizen of the United States, residing at Buffalo, in the county of Erie and State of New York, have invented certain new and useful Improvements in Clamps for Molders' Flasks, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of my invention is to provide a suitable clamp for molders' flasks or other purposes which is capable of exerting the necessary force of a screw at the point required and of being instantly released from 20 the screw, so that the clamping-pieces may be easily moved to and fro to accommodate them to flasks or other articles of different depths, whereby the force of a screw is only used where a clamping-power is required, all of 25 which will be fully and clearly hereinafter described and claimed, reference being had to the accompanying drawings, in which—

Figure 1 is an inside elevation of the clamp. Fig. 2 is an outside elevation of the same. 30 Fig. 3 is a partial enlarged inside elevation with the sliding portion removed. Figs. 4 and 5 are sectional elevations illustrating the operation, and Fig. 6 shows a modified form of the device.

35 Referring to the drawings, a is one of the clamping-bars, having at one end a clamping-piece a' , and is provided with a longitudinal slot a^2 and depressions a^3 a^3 at each side of the slot, forming a slideway in which the other 40 clamping-bar b slides. At the open end of the clamping-bar a is a projecting case a^4 , having an interior curved recess a^5 and the curved open sockets a^6 a^6 on either side of the recess a^5 . The clamping-bar b consists of 45 a bar adapted to slide to and fro in the slideway a^3 a^3 , and is provided on its back with a longitudinally - arranged segmental female screw-thread b' and upon the opposite side a longitudinal central rib b^2 , and at outer end 50 is the clamping-piece b^3 .

C is a cylindrical portion provided with

trunnions C' C' , one of which is provided with a lever or thumb-piece C^2 . Upon the portion C is a segmental male screw-thread C^3 , which screw only extends part way around, being 55 cut away even with the surface of the cylindrical portion C at C^4 , (see Fig. 3,) so that when the screw-thread C^3 is in engagement with the female screw b' , as shown in Fig. 5, the clamping-pieces are drawn to or from each 60 other by the power of a screw while turning the cylindrical portion C either way by means of the lever C^2 , and when disengaged, as shown in Fig. 4, by turning the lever C^2 back far enough to release the male screw from the 65 female screw the clamping-bar a is free to slide either way in the slideway a^3 a^3 —that is, when the portion of the cylinder C from which the screw-thread C^3 is cut away is opposite the segmental female screw, there is 70 nothing to hold the clamping-bars from being moved easily and adjusted to the article to be clamped—after which the power of the screw is applied by turning the lever C^2 so as to bring the screws into engagement, as before 75 mentioned.

In Fig. 6 I have shown the device provided with fastening-lugs d , with which to secure it to the edge of a carpenter's or other bench for the purpose of securing or clamping an 80 object between the clamping-pieces.

From the foregoing description it will be noticed that the power of a screw is only exerted for a short distance, and only at the point when a screw-power is required to clamp 85 an object tightly.

I claim as my invention—

1. A clamp for molders' flasks or other purposes, consisting of a slotted bar provided with a clamping-piece at one end and at the 90 opposite end a case a^4 , in combination with a bar constructed to slide longitudinally back and forth along the slotted bar, and provided with a clamping-piece at one end and at the back with a segmental female screw, and a 95 cylinder C , having a lever C^2 mounted in the case a^4 , and provided with a male screw-thread C^3 , extending partly around it, so that it gears in with the female screw during a part of its rotation only, whereby when the 100 lever is turned over to one side it engages with the female screw, and when turned back

the other way it is released from the screw, so that both clamping-pieces may be easily and freely moved longitudinally to or from each other, substantially as described.

5 2. A clamp for molders' flasks, &c., consisting of the slotted clamping-bar a a^2 , having the clamping-piece a' and interior slideway a^3 a^4 , the clamping-bar b , having the segmental female screw-thread b' , clamping-piece b^3 , and rib b^2 , and cylinder C , with trunnions C' C' , lever or thumb-piece C^2 , and male screw C^3 , located in the projecting case a^4 of clamping-bar a , all combined and operating substantially as shown and described.

15 3. A clamp for molders' flasks, &c., consisting of the slotted clamping-bar a a^2 , having

clamping-piece a' and slideway a^3 a^4 , clamping-bar b , having the segmental female screw-thread b' , clamping-piece b^3 , and the cylinder C , with trunnions C' C' , lever or thumb-piece C^2 , and male screw C^3 , for the purpose stated, located in the projecting case a^4 of clamping-bar a , all combined and operating substantially as shown and described.

In testimony whereof I have signed my name to this specification in the presence of two subscribing witnesses.

EDWARD E. JOSEF.
